UNITED STATES PATENT OFFICE.

SVEN O. MYRBERG, OF EAST PROVIDENCE, RHODE ISLAND, ASSIGNOR TO PROVIDENCE STOCK COMPANY, OF PROVIDENCE, RHODE ISLAND, A CORPORATION OF RHODE ISLAND.

BRACELET END HOOK.

Application filed September 21, 1926. Serial No. 136,834.

This invention relates to a bracelet end hook of a type more particularly adapted for attaching the end of a watch bracelet to the bail of a wrist watch; and the object 5 of the invention is to provide a sliding tongue for closing the hook portion which extends through the bail of a wrist watch with means for holding the tongue in either open or closed position.

10 With these and other objects in view, the invention consists of certain novel features of construction, as will be more fully described, and particularly pointed out in the appended claims.

15 In the accompanying drawings:

Figure 1 is a top plan view of a wrist watch with a portion of the bracelet connected to one of the bails thereof by a bracelet hook forming the subject matter of this 20 invention.

Figure 2 is a perspective view of a portion of the body with the hook carried thereby.

Figure 3 is a perspective view of the bottom wall of the body of the end hook.

25 Figure 4 is a perspective view of the sliding tongue for closing the hook.

Figure 5 is a sectional side elevation showing the tongue in closed position.

Figure 6 is a sectional side elevation showing the tongue in open position.

Figure 7 is a sectional end elevation on line *a—a* of Figure 5.

Figure 8 is a sectional side elevation of a modified form of hook.

30 Figure 9 is a perspective view of a still different modified form of hook.

Figure 10 is a perspective view of the sliding tongue used in the construction of hook illustrated in Figure 9.

40 It is found in the use of bracelet hooks of the character adapted to attach a watch bracelet to the bails of a wrist watch, of advantage to provide a sliding tongue for closing the hook and also of advantage to

45 provide means for frictionally holding the tongue in either closed or open position with a finger-piece for manipulation of the tongue which extends through one of the walls of the body for engagement, and in

50 order to accomplish such holding in different positions, I have provided a detent on the sliding tongue to snap by an abutment on the body of the hook to engage either side thereof to hold the tongue in either

open or closed position; and the following 55 is a detailed description of one construction of hook by which these advantageous results may be accomplished:

With reference to the drawings, 10 designates a wrist watch having bails 11 to 60 which is attached a flexible bracelet 12 by means of an end hook 13. This end hook comprises a top wall 14 having an extended shank portion 15 provided with a hook-shaped end 16. The top wall is slotted as 65 at 17 for the purposes hereinafter described. Side walls 18 are also provided extending from the top wall 14 and suitable means such as an end wall or bar 19 may be provided for attaching the hook to the end link of 70 a flexible bracelet.

The bottom wall 20 of the body has side walls or flanges 21 which space it from the top wall and are mounted between the side 75 walls of the top, the edges 22 being rolled over to hold the bottom wall in position.

Slidably engaging the top wall and between it and the bottom wall of the body, there is a tongue 23 mounted, the same having an offset end portion 24 to substantially meet the hook-shaped end 16 to close the same. The tongue is also provided with flanges 25 to slidably engage the side walls of the body to guide the tongue in its movement and to strengthen the same. A finger-piece 26 is 80 carried by the tongue and extends through the slot 17 in the top wall for manual engagement to slide the tongue to open or close the hook.

Portions 27 of the tongue are raised from the stock thereof to provide projections or 85 detents which are sufficiently resilient to snap by the abutment portion 28 projecting from the bottom wall to engage either side thereof and frictionally hold the tongue in 90 opened or closed positions.

The resilient projections or detents may 95 be formed in various ways and in Figure 8 I have illustrated a single detent 29 as cut from the stock and raised in a manner to engage the bottom wall to frictionally hold the tongue in the desired position, it being also 100 illustrated in this figure that the finger piece 30 extends through the bottom wall of the hook rather than through the top wall as is 105 shown in the previously described figures.

In Figure 9 a construction of end hook is disclosed which supplies wings for the

watch and the portion 31 which extends through the bail is to be considered the hook within the terms of this specification and claims as by the term "hook" I mean any portion which extends through the bail of a wrist watch. The portion 32 of this modified form of hook abuts the face of the wrist watch to close the opening between the watch case and the bail, and the finger-piece 10 33 is illustrated in this form as extending through the side wall 34 of the hook so as to leave the top wall uninterrupted for ornamental purposes, the tongue 35 which is slidable in this modified form of hook has a 15 resilient projection 36 to engage the bottom wall 37 to retain the sliding tongue in any desired position. Any means such as a slot 38 may be provided for attaching this hook to the end of a bracelet.

20 From the foregoing it will be seen that I have provided a bracelet end hook having a sliding tongue which is positively locked in opened or closed positions, and has a finger-piece extending through a wall of the 25 bracelet for operating the same.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A bracelet end hook comprising a hollow body, a hook carried by said body, a tongue having a portion in said hollow body and slid able to close said hook, a finger-piece extending from the body for manually operating the tongue, and means for retaining said tongue in either open or closed positions.
2. A bracelet end hook comprising a hollow body, a hook carried by said body, a tongue having a portion in said hollow body and slid able to close said hook, a finger-piece extending through one of the walls of the body for manual engagement to slide said tongue, and resilient detent means between

said tongue and body to frictionally retain said tongue in opened or closed position. 50

3. A bracelet end hook comprising a hollow body, a hook carried by said body, a tongue having a portion in said hollow body and slid able to close said hook, a finger-piece extending through one of the walls of the body for manual engagement to operate said tongue, a resilient projection on said tongue for engaging a portion of said body to frictionally retain said tongue in opened or closed positions. 55

4. A bracelet hook comprising a body having a top wall extended to form a shank with a hook-shaped end, a bottom wall spaced from the top wall, a portion extending from said bottom wall to form an abutment, a tongue slidably mounted between said walls for closing said hook end, and a resilient projection carried by said tongue to engage either side of said abutment to hold said tongue in opened or closed position. 60

5. A bracelet end hook comprising a body having a top wall with an opening therein, and extended to form a shank with a hook-shaped end, a bottom wall spaced from said top wall and having portions folded to form an end wall for said body, a tongue closing the hook and having a portion slid able in said body between said top and bottom walls, a resilient projection raised from the stock of said tongue for snapping by said end wall of the body to engage either side thereof and hold said tongue in opened or closed positions, and a finger-piece carried by said tongue and extending through said opening for manually operating said tongue. 70 75

6. A bracelet end hook comprising a body having a top wall extended to form a shank with a hook-shaped end, a tongue slid able along said top wall and having a portion offset to engage and close the end portion of said hook-shaped shank end, means for retaining said tongue in opened or closed positions, and a finger-piece for operating said tongue. 80 85

In testimony whereof I affix my signature.

SVEN O. MYRBERG.
